(57) **CLAIM**

The ornamental design for an air treatment device, as shown and described.

DESCRIPTION

FIG. 1 is a perspective view of a first embodiment of an air treatment device showing our new design;
 FIG. 2 is a first side view thereof;
 FIG. 3 is a second side view thereof;
 FIG. 4 is a third side view thereof;
 FIG. 5 is a fourth side view thereof;
 FIG. 6 is a bottom view thereof;
 FIG. 7 is a top view thereof;
 FIG. 8 is a perspective view of a second embodiment of an air treatment device showing our new design;
 FIG. 9 is a first side view thereof;
 FIG. 10 is a second side view thereof;
 FIG. 11 is a third side view thereof;
 FIG. 12 is a fourth side view thereof;
 FIG. 13 is a bottom view thereof; and,
 FIG. 14 is a top view thereof.

The broken lines shown within the figures form no part of the claimed design.
